JOHN JOSHUA ARMSTRONG, SR., OF WEIMAR, TEXAS, ASSIGNOR OF ONE-HALF TO EVERETT MCASHAN AMMANN, OF WEIMAR, TEXAS.

ADJUSTABLE HOE.

1,147,913.

Specification of Letters Patent. Patented July 27, 1915.

Application filed July 18, 1914. Serial No. 851,790.

To all whom it may concern:

Be it known that I, JOHN J. ARMSTRONG, Sr., a citizen of the United States, residing at Weimar, in the county of Colorado and State of Texas, have invented a new and useful Adjustable Hoe, of which the following is a specification.

The invention relates to improvements in hoes.

10 The object of the present invention is to improve the construction of hoes and to provide a simple, practical, and inexpensive hoe, of strong and durable construction, equipped with an adjustable blade adapted 15 to be arranged to form either a chopping hoe or a scuffle hoe, and capable, when arranged as a chopping hoe, of adjustment to set the blade at different angles to suit any kind of soil.

20 With these and other objects in view the invention consists in the construction and novel combination of parts hereinafter fully described, illustrated in the accompanying drawing, and pointed out in the claim appended hereto, it being understood that various changes in the form, proportion, size and minor details of construction, within the scope of the claim, may be resorted to without departing from the spirit or sacrificing 25 any of the advantages of the invention.

In the drawing:—Figure 1 is a perspective view of a hoe constructed in accordance with this invention. Fig. 2 is a central longitudinal sectional view of the same. Fig. 3 is a plan view of the hoe. Fig. 4 is a side elevation of the hoe, the blade being arranged to form a scuffle hoe.

35 Like numerals of reference designate corresponding parts in all the figures of the drawing.

In the accompanying drawing, in which is illustrated the preferred embodiment of the invention, 1 designates a hoe blade provided with an attaching bracket or flange 2 45 consisting of a plate or piece split at the outer portion and bent at right angles in opposite directions to form laterally projecting attaching lugs or ears 3. The laterally projecting lugs 3, which are fitted 50 against the rear face of the hoe blade 1, are secured to the same by rivets 4 or other suitable fastening devices at the upper portion of the hoe blade when the latter is arranged to form a chopping hoe. The outer side edge 55 of the projecting flange 2 is arranged con-

tiguous to the upper edge of the hoe blade, and a handle 5, which is provided with a metallic shank or stem 6, is pivotally connected to the flange 2 by a rivet 7 or other suitable fastening device to permit the blade 60 to be arranged at different angles when used as a chopping hoe, and also to be adjusted to a position in substantial alinement or parallelism with the plane of the handle to form a scuffle hoe, as illustrated in Fig. 4 of the 65 drawing.

The shank 6, which is preferably squared, has a slight longitudinal curve, and its outer portion is split or bifurcated to provide a slot or opening 8 to receive the flange of the 70 hoe blade. The flange extends into the slot or opening and is adjustably secured to the shank by means of a pivot hook 9 and a split spring key 10. The hook 9, which is arranged at the upper edge or face of the 75 shank when the blade is adjusted to form a chopping hoe, is pivoted at the inner end of its shank to the shank 6 of the handle by a rivet 11 or other suitable fastening device. The pivot is located at the inner portion of 80 the shank and the hook extends outwardly therefrom to a point beyond the inner end of the slot or opening 8, the bill 12 being adapted to extend across the slot or opening 8 and engage one of the arcuate series 85 of perforations 13 at the terminal portion of the flange 2. The flange 2 may be provided with any number of perforations to secure the desired angular adjustment of the 90 hoe blade, and the shank is provided with a transverse perforation 14 extending through both sides of the bifurcated outer portion of the shank and adapted to aline with the perforations 13 and receive the key 10. The key 10 is passed through one of the perforations 95 13 and the perforation 14, while the hook 9 engages another of the said perforations 13, whereby the flange of the blade is secured to the shank of the handle by a double locking means. The shank 6 is provided at a point between the pivot 7 and the perforation 14 with a perforation 15 adapted to register with a perforation 16 of the flange to receive the key 10 for securing the hoe blade 1 in position to form a scuffle 105 hoe. When the hoe blade is arranged to form a scuffle hoe, the shank 6 of the handle abuts against one of the laterally projecting attaching lugs of the flange, and is securely fastened in such position by the key 110

10, which spreads, through its resiliency, to retain it in the said perforations 15 and 16. When the blade is arranged as a scuffle or 5 weeds under fences and various other places inaccessible to a chopping hoe. The shank 6 is provided with a threaded tang or attaching portion 17, which is secured in the outer end of the handle 5.

10 What is claimed is:—

A hoe of the class described including a 15 hoe blade, a relatively narrow flange projecting from the hoe blade and provided with an inner perforation and having an outer arcuate series of perforations, a handle provided with a shank bifurcated to receive the flange and pivoted to the same, 20 said shank having inner and outer perforations, the outer perforation being adapted to register with the inner perforation of the

flange when the blade is arranged to form a scuffle hoe, a key carried by the shank and adapted to engage the said registering perforations, and a hook pivotally mounted on the shank and arranged to engage the perforations of the arcuate series for securing the blade at different angles to the handle, said key being also adapted to be arranged in the inner perforation of the shank and one of the arcuate series of perforations of the flange in the angular adjustment of the blade. 25

In testimony, that I claim the foregoing as my own, I have hereto affixed my signature in the presence of two witnesses.

JOHN JOSHUA ARMSTRONG, SR.
